UNITED STATES PATENT OFFICE.

ROBERT W. VAIL, OF NEW YORK, N. Y., ASSIGNOR OF ONE-HALF TO CLIFFORD W. HARTRIDGE, OF NEW YORK, N. Y.

ASH AND GARBAGE, DUSTLESS, AND ODORLESS BARREL.

1,216,022.

Specification of Letters Patent. Patented Feb. 13, 1917.

Application filed February 12, 1915. Serial No. 7,911.

To all whom it may concern:

Be it known that I, ROBERT W. VAIL, a citizen of the United States, residing at New York, in the county of New York and State of New York, have invented a new and useful Ash and Garbage, Dustless, and Odorless Barrel, of which the following is a specification.

My invention has for its object the creation of more sanitary conditions in devices for holding ashes and garbage previous to its collection. It is further my object to provide a novel barrel supplied with a novel, practical and durable cover, arranged to keep dust and odors from escaping from the barrel and to prevent the entrance of germ-carrying flies; and it is my purpose to provide a barrel arranged for the sanitary dumping thereof into the ash cart which I have devised and which is set forth in my co-pending application, Serial No. 7,910. It is further my object to provide a barrel arranged so that it can be speedily rolled from the house to the curb, and to provide a cover supplied with means for attaching disinfecting apparatus. Other objects of my invention will appear hereinafter.

I attain the objects of my invention by the mechanism illustrated in the accompanying drawings, in which—

Figure 1 is a side elevation of the barrel, with the cover on; Fig. 2 is a top plan, with the cover on; Fig. 3 is a section on line 3—3 of Fig. 2; Fig. 4 is a detail of the barrel applied to the cart, with cover in closed position; Fig. 5 is a detail similar to Fig. 4 but with the cover in open position; and Fig. 6 is a detail of member 172.

Like numerals designate like parts through the views.

Referring to the accompanying drawings, I provide a barrel body 134, preferably of cylindrical form, having a bottom 149 and a cover 140. The barrel body is reinforced by vertical supports or braces 135 having outturned portions 137, as shown in Fig. 3. Bolted to portions 137 is a reinforcing bottom ring 136 having a beveled portion 153, to facilitate the rolling of the barrel on the ground. The barrel is further provided with an internal brace member 182, which extends down opposite sides and across the bottom, as illustrated in Fig. 3. It relieves the strain incident to the application of the

barrel to the cart during the emptying operation. It is positioned in substantial alignment with members 181 and 108. The bottom 149 of the barrel is reinforced beneath by a brace member 150 having downturned ends 151 by which it is secured to reinforcing ring 136 by bolts 152.

My barrel is provided with opposite vertical handles 138, mounted on braces 135, and opposite horizontal handles 147 attached to revoluble ring 143, as shown in Fig. 1. Ring 143 is mounted on an inner rigid ring 144 which is attached to the barrel. Ring 144 is provided with a groove 145 in its outer face to receive the semispherical ends of pins 146 which are mounted in revoluble ring 143 and retain it in place to allow it to revolve on ring 145. There are from four to eight pins 146.

Referring to Fig. 3, I provide a top ring 109 having an annular horizontally projecting portion 148, and an upwardly extending annular portion 139 on the flat upper surface of which (which is parallel with the end of the barrel body upper edge,) rests cover 140. Cover-holders 172 are provided, as shown, to engage over the top of cover 140, having springs 174 engaging against the cover. A removable pin 175 holds the cover over the barrel normally, by keeping it from sliding out of engagement with springs 174 of the overlapping clips 172. The cover is further provided with a projection 160, adapted to engage in a corresponding recess in a cover operating member of the cart mechanism with which this barrel is used and which is set forth in detail in my copending application relating to the cart. Attached to member 109, are suitable arms 180, as shown in Fig. 2, which support a rod 181, which is adapted to engage in a hook like holding member of the cart mechanism set forth in my copending application and illustrated therein and also in Figs. 4 and 5 of this application. Opposite to member 181 is a suitable lug 108, as shown in Figs. 2 and 1, by means of which the barrel is secured to the cart, as illustrated in Figs. 4 and 5.

Cover 140 is further provided with a threaded aperture 170, to permit of connection with any suitable disinfecting apparatus when the cover is on and the barrel approximately hermetically sealed. Aperture 170 when not in use is closed by a screw 110.

plug 177, having a suitable depression 178 for engagement with a screw driver. The top of member 177 normally sets flush with the top surface of cover 140. The outer or 5 peripheral edge or surface 177' of cover 140 engages against contact edge 176 of cover holders 172, as illustrated in detail in Fig. 6. The angular construction of member 172, as 10 illustrated prevents clogging when the cover is moved into position over the barrel, as the edge 176 operates to crush any obstructing material which may lodge between the edge of the cover and the cover holder.

In taking cover 140 off by hand, or previous 15 to attachment to cart, pin 175 is first removed, which permits cover 140 to be withdrawn. In placing the barrel in its position in connection with the cart, the barrel is lifted by handles 147, and rod 181 is engaged 20 in the hook-like member 196 of the cart and swung upward and locked in operative position to the cart by the engagement of members 181 and 108 of the barrel with fastening devices on the cart, as illustrated. Brace 25 member 182 takes up the strain incident during the varying operative position of a loaded barrel attached to the cart. The projection 160 of cover 140 is engaged by an elevatable member of the cart mechanism, by 30 which the cover is elevated into housing 154, to permit of dumping of the contents of the barrel into the cart. The revoluble ring 147 permits of easy operation of the barrel in rolling it to the cart, as the person rolling 35 the barrel grasps handles 147 which are held stationary while the barrel revolves, as he rolls it along, on the beveled portion 153 of the bottom ring 136.

What I claim is:

- 40 1. A garbage barrel having a reinforcing brace attached to its base and having a reinforcing ring between opposite portions of which the brace member extends, the ring having a beveled portion, and a rolling support for the barrel rotatably engaging the outer portion of the barrel to permit of readily rolling the barrel.
2. A garbage barrel having an upper reinforcing ring, a bottom reinforcing ring, oppositely arranged cart-engaging members for 45 engaging the barrel to the cart, longitudinal brace members alined with the cart engaging

members and extending from the upper to the bottom reinforcing ring, and a transverse brace member alined with the longitudinal brace members and secured to the bottom of the barrel, for the purposes described. 55

3. The combination with a garbage receptacle having oppositely arranged means for supporting the receptacle in elevated position, of an internal brace member alined therewith reinforcing the sides and bottom of the inner portion of the receptacle, reinforcing rings positioned at the upper and bottom portions of the receptacle, oppositely arranged vertical reinforcing members extending between and attached to the aforesaid rings, and a bottom brace member in alinement with opposite vertical brace members, for the purposes described. 60

4. A garbage barrel having an upper reinforcing ring, a bottom reinforcing ring, the bottom ring having a beveled portion for contact with the ground when the barrel is being rolled, a plurality of oppositely arranged vertical braces extending between and affixed to the horizontal reinforcing rings, oppositely arranged cart-engaging means at one end of the barrel for raising it to elevated position, the vertical braces and the barrel raising means being alined, and bottom bracing means affixed to the bottom reinforcing ring at opposite portions thereof and alined with opposite vertical brace members, whereby to substantially reinforce the 75 barrel. 80

5. In combination with a barrel, a reinforcing upper ring having an annular outwardly projecting portion spaced below the upper edge of the barrel, an annular portion 90 in alinement with the upper edge of the barrel to provide a support for the cover, and an annular downwardly projecting portion to which a plurality of brace members are secured, oppositely arranged cart-engaging 95 means on the upper ring for raising the barrel from the ground, and oppositely arranged brace members alined therewith to reinforce the barrel, for the purposes set forth.
